J. F. HILL.
AUTOMOBILE TOP DECK PROTECTOR.
FILED MAR. 30, 1922.

Fig. 1.

Patented Dec. 19, 1922.

1,439,238

UNITED STATES PATENT OFFICE.

JOHN F. HILL, OF ROCHESTER, INDIANA.

AUTOMOBILE TOP-DECK PROTECTOR.

Application filed March 30, 1922. Serial No. 548,162.

To all whom it may concern:

Be it known that I, JOHN F. HILL, a citizen of the United States, residing at Rochester, in the county of Fulton and State of Indiana, have invented certain new and useful Improvements in Automobile Top-Deck Protectors, of which the following is a specification.

My invention relates to protectors to be applied to the bows of vehicle tops.

An important object of the invention is to provide a protector of the above mentioned character, which may be applied to the top of the bow, and having a substantial width, will project laterally upon opposite sides of the bow, this protector being so constructed that it will not tend to wear or cut through the top or deck of the vehicle top.

A further object of the invention is to provide a device of the above mentioned character, which is extremely simple in construction, strong and durable.

Other objects and advantages of the invention will be apparent in the course of the following description.

In the accompanying drawings forming a part of this specification and in which like numerals are employed to designate like parts throughout the same.

Fig. 1 is a perspective view of the top of the vehicle, having my improved protectors applied to the bows,

Fig. 2 is a side elevation of a protector, embodying my invention, showing the same in use,

Fig. 3 is a plan view of the protector,

Fig. 4 is a transverse section through the protector,

Fig. 5 is an end elevation of the same,

Fig. 6 is a transverse section through a slightly modified form of the protector.

In the drawings, wherein for the purpose of illustration is shown a preferred embodiment of my invention, the numeral 10 designates the top of the vehicle, such as an automobile, the deck or top portion 11, being supported by bows 12, as shown. The bows, as is customary, are relatively narrow, and frequently wear or tear through the fabric in the top portion or deck 11.

The numeral 13 designates my improved protectors, as a whole, which are mounted upon the top of the bows 12, and are of a sufficient width, to project laterally beyond the bows for substantial distances. The pro-

tector includes a holding member or base 14, preferably formed of sheet metal, while the same may be formed of any other suitable material. This base is preferably slightly curved in cross section, extending downwardly toward its outer edges. The base 14 has its outer edges bent upwardly in the form of flanges 15, which are curved or U-shaped in cross section. These flanges continue throughout the entire length of the edges of the base 14. The base is tapered at its ends, as clearly shown in Fig. 5. The base is also preferably substantially straight throughout its greater portion of its length, but the tapered end portions are curved downwardly, as shown. It is obvious that the longitudinal curvature or shape of the base will depend entirely upon the shape of the bow, upon which the base is to be applied.

The base 14 receives and holds an upper lining 16 of fibrous material, which may be felt, cloth, hair, leather or the like. This lining has its edges held within the curved flanges 15, as shown.

In the application of the protector upon the bow, the padding 17 of the top is suitably slit, so that the ends of the protector may be inserted through this slit into the padding, and rest in close contact upon the bow. The protector is secured to the bow by screws 18 or the like and these screws preferably have their heads countersunk or flush with the upper surface of the lining 16, so that they cannot injure the top portion or deck 11.

In Fig. 6, is shown, a modification of the protector. In this figure the numeral 19 designates the base, which is identical with the base 14. The edges of this base are bent into the flanges 20, curved in cross section, and identical with the flanges 15. The base 19 receives fibrous lining 21, identical with the lining 16, and the device is held upon the bow 12 by screws 22 or the like.

In this form of protector, the material of the base 19 is continued at the edges of the flanges 20, in the form of sides 23, integral therewith, and these sides have bottom portions 24, which overlap, and are screwed to the bottom of the bow by screws 25 or the like. This construction is stronger, and by virtue of the rounded sides 23, it is more suitable for a top which is to be folded.

In view of the foregoing description, it is obvious that the protector is secured to

the bow between it and the top portion 11, and by virtue of the large transverse area of the protector and its fibrous lining, the same will not injure the top portion or 5 deck.

It is to be understood that the forms of my invention herewith shown and described are to be taken as preferred examples of the same, and that various changes in the shape, 10 size, and arrangement of parts, may be resorted to, without departing from the spirit of my invention or the scope of the subjoined claims.

Having thus described my invention, I 15 claim:

1. A protector to be arranged upon the bow of a vehicle top, comprising a base extending laterally beyond the bow, said base having its edges bent upwardly into retaining 20 flanges having overhanging edges, a fibrous lining arranged upon the upper surface of the base and having its edges held against vertical displacement by the over-

hanging edges of the retaining flanges, said base being inclined in cross section downwardly toward the retaining flanges whereby the overhanging edges thereof are positioned beneath the upper surface of the central portion of the fibrous lining, and attaching elements passing through the fibrous 30 lining and base and anchored within said bow.

2. A protector to be arranged upon the top of the bow of a vehicle top, comprising a base, said base having its material bent at 35 its edges into retaining flanges, said material being extended downwardly from the flanges in the form of sides having horizontal portions, a fibrous lining arranged upon the base and held by the flanges, means to 40 secure the base to the bow, and means to secure the horizontal portions of said sides to the bow.

In testimony whereof I affix my signature.

JOHN F. HILL.
